UNITED STATES PATENT OFFICE.

EDWARD T. SCHOONMAKER, OF NEW YORK, N. Y., ASSIGNOR TO J. S. CONOVER & CO., OF SAME PLACE.

DESIGN FOR A FIRE-PLACE FRONT.

SPECIFICATION forming part of Design No. 15,837, dated February 17, 1885.

Application filed December 5, 1884. Term of patent 7 years.

To all whom it may concern:

Be it known that I, EDWARD T. SCHOONMAKER, of the city, county, and State of New York, have invented a certain new and ornamental Design for Fire-Place Fronts; and the following is declared to be a description of the same.

My design is fully shown in the accompanying photograph.

10 In this design the frame, the basket, the crown-piece, and the fender are especially designed to go together in the production of an artistic effect. The fire-place frame has an outer plain surface, *a*, and inner surface, *b*, with a beaded edge. At *c* there is a molded design consisting of astragal ornaments. The fire-place frame has moldings and a plain base at *d*. The moldings *e* pass across the frame. The upper portion of the frame is ornamented 15 by convoluted stems, leaves, and flowers in relief upon the panels. The ornaments in the panels *f* and *f'* are alike, and in *g* and *g'* they are alike. All these panels have a background in imitation of hammered or stippled 20 work, and upon this background are the raised floricultural designs consisting of stems, leaves, flowers, and buds, as shown. Below the moldings *e* the panels *i* are divided by perpendicular and cross ribs into squares, in 25 which squares there are quarterfoil ornaments with central buttons.

The design for the basket portion consists of the molded top rail, *k*, and the ornamental bottom rail, *l*, and the perpendicular bars *m*, 30 having leaf and rosette designs, as shown.

The design for the crown-piece consists of the plain upper rail, *n*, the cross-grooved base, *o*, and end pieces, between which there are panel 35 ornaments consisting of stems and leaves in 40 serpentine form at *o'*, with a shell medallion at *p*.

The design for the fender portion consists of the flat polished plate *q*, having diverging lines, the surrounding frame having a plain surface, *r*, and molded edge *r'*, the lower 45 base-molding, *s*, the intermediate ornamental molding having oval figures and ribs, and leaf designs, as shown at *t*. The ornamental pillars *u* are upon the fender, as shown, and upon them is the ornamental twisted bar *v*. 50

In this fire-place front the ornamental design of the frame, grate, crown-piece, and fender harmonize, so as to produce an artistic effect as a whole, the ornaments *c* of the frame and *t* of the fender, the ornaments *i* of the frame and *m* of the basket, and the scroll designs *o'* of the crown-piece, pillars *u* of the fender, and ornaments *f' g h* of the frame harmonizing.

I claim as my invention—

1. In a design for a fire-place front, the ornamental frame consisting of the surfaces *a b*, astragal design *e*, moldings and panels having the raised floricultural designs, and the cross-bars and quarterfoil ornaments, as shown. 65

2. In a design for a fire-place front, the design consisting of the ornamental frame, basket and fender having the ornaments in relief, and the moldings *e l s*, substantially as described and shown.

3. The design for the ornamental fire-place front, consisting of the frame, basket, crown-piece, and fender, substantially as described and shown.

Signed by me this 1st day of December, A. 75 D. 1884.

EDWARD T. SCHOONMAKER.
